Charles R. Searle.

UNITED STATES PATENT OFFICE.

PAUL A. WAGNER, OF JERSEY CITY, NEW JERSEY.

HEDDLE FOR LOOMS.

1,413,949.

Specification of Letters Patent. Patented Apr. 25, 1922.

Application filed September 8, 1921. Serial No. 499,132.

To all whom it may concern:

Be it known that I, PAUL A. WAGNER, a citizen of the United States, residing at Jersey City, in the county of Hudson and State of New Jersey, have invented a certain new and useful Improvement in Heddles for Looms, of which the following is a specification.

The object of the invention is to provide 10 a light, economically manufactured heddle, having the required strength and flexibility and adapted to serve efficiently with the warp threads and loom harness.

The invention consists in certain novel 15 features of construction by which the above objects are attained, to be hereinafter described and claimed.

The accompanying drawings form a part 20 of this specification and show several forms of the invention.

Figure 1 is a face view of a preferred form of the improved heddle, on an enlarged scale.

Figure 2 is a face view on a still larger 25 scale and shows the construction of the warp-eye as in Figure 1, and is partly in section.

Figure 3 is a transverse section through the warp-eye, taken on the line 3—3 in Figure 2.

Figure 4 is a similar view taken on the line 4—4, through a portion of a mail serving to reinforce such eye.

Figure 5 is a face view of a portion of a 35 heddle, showing a modification, on the same scale as Figure 1.

Figure 6 is a face view on the same scale as Figure 2, and shows the construction of the warp-eye shown in the preceding figure.

40 It is partly in section.

Figure 7 is a transverse section taken on the line 7—7 in Figure 6.

Figure 8 is a transverse section taken on the line 8—8 in Figure 6.

45 Figure 9 is a face view of a modified form of mail, on the same scale as Figure 2.

Figure 10 is a transverse section taken on the line 10—10 in Figure 9.

Figure 11 is a face view of a portion of a 50 heddle showing another modification. It is on the same scale as Figure 1.

The heddles shown are formed preferably of strips of strong paper suitably treated, folded lengthwise along each margin and 55 cemented with its edges brought together to abut on one face, thus insuring smoothly

rounded edges for the heddle, and forming two layers of paper joined face to face. The heddle eyes and warp-eyes are formed by slitting and spreading the folded strip at 60 proper intervals, and the eyes are reinforced by suitable mails introduced between the layers in the process of folding and cementing the strip. Although paper is the preferred material, cotton, linen, silk or other fabric stiffened by suitable sizing or cement and similarly folded, may be employed successfully.

Referring to the drawings, Figures 1 to 4 inclusive, 12 is a strip of paper coated 70 with any suitable waterproof cement, folded longitudinally upon itself along both margins with its edges abutting along the central line. In the process of manufacture the strip is slit on such line at proper intervals, and the edges of such slits, and the abutting edges of the strip at points coinciding with the slits, are separated to form eyes which are reinforced by mails. The mails at the ends of each heddle are shown 80 as plates 13 of metal or other wear-resisting material, each having a central slot 14 serving to receive the heddle bars, not shown; and a similar but smaller mail, not shown, may be introduced at the midlength 85 to serve as a reinforcement for the warp-eye.

It is preferable to form the mails for the warp-eye in separate halves 15, see Figures 90 1 and 2, each a plate having one end 16 hollowed into crescent shape, placed in the strip in separated pairs with the curved ends 16 presented toward each other, one at each end of the warp-eye, and smoothly rounded to receive a warp thread between them.

In order to increase the tensile strength of the heddle, strands 17 which may be threads or cords are laid in the bights of the folds and held by the cement in the process of manufacture, extending the full 100 length of the heddle, and as an additional reinforcement, longitudinally extending filaments 27 of silk or other strong fibres are cemented on the surfaces of the strip, as indicated in Figure 2.

In the form of the invention shown in Figures 5 to 8 inclusive the margins of the strip are folded unequally longitudinally so that the abutting edges come together on a line at one side of the centre, as at 19, and the bight of the wider fold is cut away at 20 to receive a warp-eye formed in a plate

21 having a laterally protruding portion 22 in which is a slot 23 serving as the eye. In this form a single reinforcing strand 24 is shown lying in the bight of the narrower 5 fold.

The modification shown in Figure 11 is similar to that just described, but the offset portion of the plate or mail 25 projects beyond the margin of the heddle through a 10 slit in the bight of the wider fold.

Figures 9 and 10 show a mail formed by a closed loop or link 26 of wire, flattened as in Figure 10, and adapted to serve as a substitute for the separated mails 15 in Figures 1 and 2 or for the mails 13 for the 15 heddle bars.

The finished and dried heddle thus constructed is light, strong, and sufficiently flexible, and may be exceedingly thin and 20 narrow and is easily and cheaply manufactured in continuous lengths by suitable machinery, and subsequently cut to produce the individual heddles shown.

Other modifications than those shown and 25 described may be made; fine wires may be substituted for the strands 17 and 24, the filaments 18 may be omitted, and the forms and proportions of the parts varied as conditions of service may require.

30 I claim:

1. A heddle composed of layers of fibrous material analogous to paper, secured together face to face and having warp-eyes therein.
2. A heddle composed of layers of fibrous material analogous to paper, secured together face to face and having warp-eyes therein, and means embodied in said layers for reinforcing said eyes.
3. A heddle composed of layers of fibrous material analogous to paper, secured together face to face and having warp-eyes therein, and reinforcing strands extending longitudinally of and attached to said 45 layers.
4. A heddle composed of layers of fibrous material analogous to paper, secured together face to face and having warp-eyes therein, means embodied in said layers for 50 reinforcing said eyes, and reinforcing strands extending longitudinally of and attached to said layers.
5. A heddle composed of two layers of fibrous material analogous to paper, cemented 55 together face to face and having eyes therein, and reinforcing strands extending longitudinally of such heddle between said layers and held by such cement.
6. A heddle composed of two layers of 60 fibrous material analogous to paper, cemented together and having eyes therein, reinforcing strands extending longitudinally of such

heddle between said layers and held by such cement, and reinforcing mails for such eyes held by such cement between said layers. 65

7. A heddle composed of two layers of fibrous material analogous to paper, cemented together and having eyes therein, and reinforcing mails for such eyes between said layers and held by such cement. 70

8. A heddle composed of a flexible strip folded upon itself longitudinally and having eyes therein, and mails inclosed by such folds and reinforcing said eyes.

9. A heddle composed of a flexible strip 75 folded longitudinally along both margins with both edges presented on the same face, and eyes in such folded strip.

10. A heddle composed of a flexible strip folded longitudinally along both margins 80 with both edges presented on the same face, eyes in such folded strip, and a reinforcing strand extending longitudinally and inclosed in a bight of such folds.

11. A heddle composed of a flexible strip 85 folded longitudinally along both margins and cemented with both edges presented on the same face, eyes in such folded strip, and a reinforcing strand extending longitudinally, inclosed in a bight of such folds and 90 held by such cement.

12. A heddle composed of a flexible strip of fibrous material analogous to paper, folded longitudinally along both margins and cemented with both edges presented on the 95 same face, eyes in such folded strip, and longitudinally extending filaments cemented to the outer faces of such folded strip.

13. A heddle composed of a flexible strip folded longitudinally along both margins 100 and cemented with both edges presented on the same face, eyes in such folded strip, and mails inclosed by such folds and held by such cement.

14. A heddle composed of a flexible strip 105 folded longitudinally along both margins and cemented with both edges presented on the same face, slits in said strip in coincidence with the joint along such edges, and mails inclosed by such folds and serving 110 to reinforce eyes formed by separating the margins of such slits and joint.

15. A heddle composed of a flexible strip folded longitudinally along both margins 115 and cemented with both edges presented on the same face, a slit in said strip in coincidence with the joint along such edges, a warp-eye formed by separating the margins of such slit and joint, and a pair of separated mails inclosed by such folds and serving 120 to reinforce the ends of such eye.

In testimony that I claim the invention above set forth I affix my signature.

PAUL A. WAGNER.
